ATTY.

UNITED STATES PATENT OFFICE.

JOHN JENKINS, OF KENNEDY, SASKATCHEWAN, CANADA.

SPOUT-SUPPORT.

1,367,548.

Specification of Letters Patent.

Patented Feb. 8, 1921.

Application filed January 22, 1920. Serial No. 353,370.

To all whom it may concern:

Be it known that I, JOHN JENKINS, of the town of Kennedy, in the Province of Saskatchewan, Canada, have invented certain 5 new and useful Improvements in Spout Supports, of which the following is the specification.

The invention relates to improvements in spout supports and particularly to a support for holding and directing a grain spout such as is required when loading a grain car and the principal object of the invention is to provide a support which will positively hold and direct the spout to effectively deliver the grain and which is arranged and constructed to suit the various requirements which may arise.

A further object is to construct the support in a simple, durable and inexpensive 20 manner and such that it can be readily handled and operated.

A still further object of the invention is to provide an adjustable support which can be set to suit the work in hand.

25 With the above more important objects in view the invention consists essentially in the arrangement and construction of parts hereinafter more particularly described and later pointed out in the appended claims, 30 reference being had to the accompanying drawings in which:—

Figure 1 is a sectional view through the grain car and showing my support as it appears in use.

35 Fig. 2 is a side view of a portion of the car and showing the parts as they appear in Fig. 1.

Fig. 3 is a side view of the spout support.

Fig. 4 is a plan view thereof.

40 Fig. 5 is a sectional view through the body part of the spout with the end pieces shown in side elevation.

Fig. 6 is a side view of the fastening band.

Fig. 7 is a front view of the band.

45 Fig. 8 is a sectional view through a grain car and showing a modified form of the spout support.

Fig. 9 is a side view of the bifurcated shank.

50 Fig. 10 is a front view of the same.

In the drawings like characters of reference indicate corresponding parts in the several figures.

This support is especially adapted for use 55 in elevator work and particularly when load-

ing cars with grain and I have accordingly herein described it as used for holding the discharge spout discharging the grain into the car.

1 represents a car, 2 the grain door thereof 60 and 3 the elevator containing the grain to be loaded into the car and which is supplied with a flexible discharge spout 4 of predetermined and suitable length. 5 represents the elevator platform. The discharge spout 65 is of common form comprising a plurality of similar tapering sections 6 having their ends slightly telescoped and all held flexibly together by side chains 7 fastened by center rivets 8 to the sides of the respective sections. 70

The end section of the spout is provided with a reinforcing collar 9 and with side grips 10. Owing to the construction of the spout it will be apparent that it can be bent at will to discharge the grain into the various 75 parts of the car.

My support is provided to hold the end of the spout in any desired position within the car. It is constructed as now described.

11 represents a body part shown in the 80 present disclosure as a pipe having the one end incased by a reinforcing collar 12 and fitted with a jam screw 13 and the other end flattened and reinforced by a sleeve 14 shank or otherwise applied on the pipe. 85 The flattened end of the pipe forms a socket for a shank 15 which has one end slidably entered within the socket and the other end provided with a bayonet slot 16.

17 represents a leg having one end telescoped within the pipe and the other end terminating in a curved piercing point 18. The length of the support can be adjusted by withdrawing or pushing in the foot and manipulating the screw 13 as will be readily observed.

19 represents an attaching band which is clamped around the last section of the spout, being preferably passed under the grips 10 and being fitted so that the clamping bolt 20 thereof is located to the underside of the spout and the lug like ends 21 and 22 of the band are spaced apart as shown in Fig. 7 when the band is tightly clamped on the spout.

After the band has been attached to the spout one enters the body of the bolt 20 in the bayonet slot 16 and is then ready to set the support to hold the pipe.

In Figs. 1 and 2, where the spout is de- 110

livering toward the end of the car, it will be seen that the pronged end of the support is pierced into the upper edge of the door 2, the leg having been previously adjusted to 5 accommodate the condition.

As the upper end of the spout is fast to the elevator it will be apparent that the support will hold the weight of the end of the spout and direct it in the proper direction 10 to discharge to the end of the car.

By piercing the pronged end of the leg into various parts of the door, sides or floor of the car and by adjusting the length of the support one can hold the spout in almost 15 any desired position. I have found, however, that when operating in the center of the car it is desirable to provide a second shank 23 which can be interchanged for shank 15. The second shank is shown in 20 Figs. 8, 9 and 10 and presents a pair of horns 24 and 25 disposed at an angle to the body of the shank. The horns are adapted to span the spout and when loading the center of the car the horns are located probably behind the third lower end section and 25 underneath the side chains, while the prong is pierced into the elevator platform. By this arrangement it will be apparent that the last few sections of the spout can hang 30 down to direct the grain to the floor of the car.

While I have shown and described the spout support as an adjustable device, I wish it to be distinctly understood that I

do not wish to be limited to the precise construction shown as the body might be non-adjustable, in which case it would take the form of a straight bar, rod or tube having a piercing point at one end and a holder for the spout at the other end. 35

What I claim as my invention is:—

1. In a spout support, a pipe having one end formed into a socket, a leg having one end slidably received within the pipe and the other end formed into a piercing point, 45 a jam screw adjustably fastening the leg to the pipe, a shank mounted in the socket and provided with a bayonet slot and an attaching band clamped around the spout and provided on the underside of the spout 50 with a bolt entering the bayonet slot.

2. In a spout support, a pipe having one end formed into a socket, a leg having one end slidably received within the pipe and the other end formed into a piercing point, 55 a jam screw adjustably fastening the leg to the pipe, a demountable non-rotatable shank entered in the socket and provided on the top side with a bayonet slot and an attaching band clamped around the spout and 60 provided on the underside of the spout with a bolt entering the bayonet slot.

Signed at Winnipeg, this 16th day of December, 1919.

JOHN JENKINS.

In the presence of—

G. S. ROXBURGH,
R. BLASDALE.
